UNITED STATES PATENT OFFICE.

JOHN TRIMBLE, OF PHILADELPHIA, PENNSYLVANIA.

CAN OPENER.

Application filed October 3, 1922. Serial No. 592,014.

To all whom it may concern:

Be it known that I, JOHN TRIMBLE, a citizen of the United States, residing at Philadelphia, in the county of Philadelphia and State of Pennsylvania, have invented 5 certain new and useful Improvements in Can Openers, of which the following is a specification.

My invention relates to can openers.

10 The objects of the invention are to provide a can opener of simple and novel construction, which may be economically manufactured and conveniently used to cut the end of a can, to provide means whereby the device may be adjusted to vary the diameter 15 of the cut, means for preventing displacement of the device from the can end, and means for causing the severed part to adhere to the opener.

20 These objects, and other advantageous ends which will be described hereinafter, I attain in the following manner, reference being had to the accompanying drawings in which—

25 Figure 1 is a side elevation of the improved can opener,

Figure 2 is an end elevation looking toward the cutter blade,

30 Figure 3 is a bottom plan view of the can opener,

Figure 4 is a central vertical longitudinal sectional view of the can opener applied to a can in the act of cutting a round opening in one end thereof, and

35 Figure 5 is an enlarged detachable sectional view of a center pin forming part of the device.

40 In the drawings, the improved can opener is shown as comprising a metallic frame 6, preferably of oblong shape. This frame may be cast in one piece, or may be produced from a strip of bar metal bent to form a bottom 7, ends 8 and a top 9 at the center of which, the ends of the strip are brought 45 together and abut as indicated at 10.

A handle 11, preferably of wood, fastened to the top of the frame, as by means of screws 12, connects the ends of the strip and produces a rigid frame. The bottom is provided with a longitudinal slot 13 extending substantially throughout its length, and a center pin 14 is mounted in the slot. This pin has an enlargement or shoulder 15 and a shank 16 extending upwardly through slot 13. The shank is preferably threaded and a

nut 17 is mounted thereon. Shoulder 15 engages the under face of bottom 7 and nut 17 engages the top face so that pin 14 may be adjusted to various positions in the slot clamped in adjusted position. 60

Pin 14 is tapered to its lower extremity and extends at an angle to the shank preferably in the direction of the length of bottom 7. A cutter blade 18 is detachably mounted on the outer face of one end 8 at 65 a lower corner of frame 6, by suitable fastenings such as screws 19. The cutter blade extends below the frame, is tapered to its lower end and has oppositely beveled cutting edges 20. 70

The center pin serves as an axis upon which the cutter blade rotates and by adjusting it toward or from the cutter blade, the device may be used to cut openings of the desired diameter upon cans of different 75 sizes.

In use, center pin 14 is forced into the center of one end of a can 22, as shown in Figure 4 of the drawings, the pin having been adjusted to extend toward the end of 80 the frame opposite that to which the cutter blade is secured. The cutter blade is forced into the end of the can, and then the frame is turned on pin 14 and one of the edges of blade 18 cuts a circular opening in the can. 85 By extending pin 14 at an angle, it prevents the device from being displaced during the cutting operation. The severed part of the can adheres to the bent end of the pin and may be lifted with the opener without 90 scraping or cutting the hands on its jagged edges.

While I have described my invention as taking a particular form, it will be understood that the various parts of my invention 95 may be changed without departing from the spirit thereof, and hence I do not limit myself to the precise construction set forth, but consider that I am at liberty to make such changes and alterations as fairly come within the scope of the appended claims. 100

Having thus described my invention, what I claim as new and desire to secure by Letters Patent is:—

1. A can opener comprising an oblong 105 frame bent from a strip to form bottom, sides and top, the bottom having a longitudinal slot; a hand grip connected to the top and joining the ends of the strip; a center pin adjustable in the slot and having 110

clamping means engaging opposite faces of the bottom, and a cutter blade carried by one side of the frame.

2. A can opener comprising an oblong frame bent from a strip to form bottom, sides and top, the bottom having a longitudinal slot; a hand-grip connected to the top and joining the ends of the strip; an angular center pin adjustable in the slot and having clamping means engaging opposite faces of the bottom; a cutter, and screws for securing the cutter to the side of the frame.
3. A can opener comprising a strip bent to form a frame; a hand grip secured to the ends of the strip; centering means on the frame, and cutting means on the frame.
4. A can opener comprising a strip bent to form a frame and having its ends abut-

ting each other; a hand grip secured adjacent the ends of the strip; centering means on the frame, and cutting means on the frame.

5. A can opener comprising a strip bent to form a frame having a bottom, sides and top, the ends of the strip abutting each other at the top; a hand grip secured to the top; centering means on the bottom, and cutting means on the frame.

In testimony whereof I have signed my name to this specification in the presence of two subscribing witnesses.

JOHN TRIMBLE.
